ABDOMINAL BODY BRACE

Philip Hillard Robbins, New York, N. Y., assignor
to Poirette Corsets, Inc., New York, N. Y.

Application May 29, 1940, Serial No. 337,913

5 Claims. (Cl. 2—41)

This invention relates to a supporting belt or abdominal body brace, and aims to provide, in a manner as hereinafter set forth means acting to firmly hold and support the abdominal muscles, with the article capable of being worn by slight figures as well as large figures for relieving such ailments as the falling of the muscles of the abdomen or as a slight hernia support.

The invention further aims to provide, in a manner as hereinafter set forth, an article of the class referred to for use by people suffering with back ailments and who need added support of the sacro-iliac ligaments.

The invention further aims to provide, in a manner as hereinafter set forth, an article of the class referred to, which when the wearer is in a sitting position, will fold with the body and muscles, but which will always go back to its original shape when the wearer resumes a standing position; which will give needed support to the wearer in post-operative cases; which when worn will provide an aid to better posture; give a better appearance to the figure; and which when worn will give an extra pull-in support by elastic means running from any given point in a diagonal manner around the body of the wearer.

The invention further aims to provide, in a manner as hereinafter set forth, an article of the class referred to, for hernia cases in which a pad may be placed and carried on the inside for sacro-iliac support.

The invention further aims to provide, in a manner as hereinafter referred to, a comfortably wearable article of the class referred to for giving aid to corpulent persons participating in rather vigorous forms of exercise such as golf and tennis.

The invention further aims to provide, in a manner as hereinafter set forth, an article of the class referred to including an elastic form fitting body part having elongated elastic resistance elements connected therewith for disposing in a semi-diagonal manner around the body of the wearer from any given part to provide for an extra pull-in support to materially increase the supporting or bracing function of the article when worn.

The invention further aims to provide, in a manner as hereinafter set forth, an article of the class referred to which is comparatively simple in its construction, form fitting, strong, durable, compact, elastic, thoroughly efficient in its use, capable of being conveniently arranged in supporting or bracing position relative to the body of

a wearer, and comparatively inexpensive to manufacture.

Embodying the aims aforesaid and others which may hereinafter appear, the invention consists of the novel construction, combination and arrangement of parts as will be more specifically referred to and illustrated in the accompanying drawings, wherein are shown embodiments of the invention, but it is to be understood that changes, variations and modifications may be resorted to which fall within the scope of the invention as claimed.

In the drawings:

Figure 1 is a front elevation of an article or garment in accordance with this invention,

Figure 2 is a rear elevation thereof,

Figure 3 is an elevation looking towards the inner face of the body part of the article when such part is split through one point thereof and extended,

Figure 4 is a vertical section on line 4—4 Figure 2, through the back of the article or garment,

Figure 5 is a horizontal section on line 5—5 Figure 2, through the back of the article or garment,

Figure 6 is a horizontal section on line 6—6 Figure 1,

Figure 7 is a vertical section on line 7—7 Figure 1,

Figure 8 is a fragmentary view in rear elevation of still another modified form of an article or garment, in accordance with this invention,

Figure 9 is a section on line 11—11 Figure 10,

Figures 10, 11 and 12 are fragmentary views in vertical section of still further modified forms of an article or garment in accordance with this invention,

Figure 13 is a fragmentary view in front elevation and broken away of an article or garment, in accordance with this invention, of a two-ply body type,

Figure 14 is a section on line 16—16 Figure 13, and

Figure 15 is a fragmentary view in vertical section of a modification of a two-ply body type article or garment in accordance with this invention.

A supporting belt or abdominal body brace, in accordance with this invention, will be hereinafter referred to as a bracing belt.

With reference to Figures 1 to 7, the bracing belt, generally indicated at 10, includes a girdle-like body part 11 formed of an endless elastic

fabric member 12 having a front portion 13, a pair of side portions 14, 15 and a back portion 16. The lower portion of the member 12 is reinforced throughout by a binder 17 which is arranged against the lower marginal portions of said member and overlaps the lower edge of the latter.

The front portion 13 of member 12 is of greater width than the portions 14, 15 and 16. The portions 14, 15 gradually decrease in width from the sides of the front portions 13 to their vertical centers and gradually increase in width from their vertical centers to their points of emergence with the back portion 16. The latter gradually increases in width from its points of emergence with the portions 14, 15 to its vertical center. The portion 13 extends below the portions 14, 15 and 16. The manner of setting up the member 12 as aforesaid in connection with the binder 17 forms the bottom edge of the body part 11 with a horizontal bottom edge part 18, a pair of oppositely extending upwardly and outwardly directed curved bottom edge parts 19, 20 and a pair of oppositely extending downwardly inclined arcuate bottom edge parts 21, 22. The part 18 is arranged at the bottom of front portion 13 between and merges into the lower ends of the parts 19, 20. The parts 19, 20 are arranged at the front part of the bottom of the portions 14, 15 and the parts 21, 22 are arranged at the rear parts of the bottom of portions 14, 15 and at the bottom of the back portion 16. The upper ends of the parts 19, 20 merge into the upper ends of the parts 21, 22. The parts 21, 22 merge into each other at their lower ends. The shape of the bottom edge of the member 12, when reinforced by the binder 17, will be as shown by Figure 3. The elastic binder 17 has its lengthwise edges secured to the member 12 by zig-zag stitching 23.

Arranged against and secured to the inner face of member 12 is a series of endless elastic fabric resistance elements of strap or tape like form. The elements are disposed in superposed relation and have their lengthwise edges secured to member 12 by zig-zag stitching. The number of the resistance elements for member 12 may be as desired and preferably will consist of four and are designated 24, 25, 26 and 27. The zig-zag stitchings for securing said elements to member 12 are indicated at 28. The element 24 has its top edge flush with the top edge of member 12. The member 27 has its bottom edge arranged above and in proximity to the binder 17. The width of the spaces between the portions of said elements which are arranged at the said front portion 13 are greater than the spaces between the portions of said elements which are arranged at the said side portions 14, 15 and the said back portion 16.

The element 25 consists of a pair of oppositely disposed downwardly inclined parts 29, 30 and a pair of oppositely disposed downwardly inclined parts 31, 32. The parts 29, 30 merge into each other at their lower ends. The parts 31, 32 merge into each other at their lower ends. The upper ends of the parts 29, 31 merge into each other. The upper ends of the parts 30, 32 merge into each other. The element 26 consists of a pair of oppositely disposed downwardly inclined parts 33, 34 and a pair of oppositely disposed parts 35, 36. The parts 33, 34 merge into each other at their lower ends. The parts 35, 36 merge into each other at their lower ends. The upper

ends of the parts 33, 35 merge into each other. The upper ends of the parts 34, 36 merge into each other. The element 27 consists of a pair of oppositely disposed downwardly inclined parts 37, 38 and a pair of oppositely disposed downwardly inclined parts 39, 40. The parts 37, 38 merge into each other at their lower ends. The parts 39, 40 merge into each other at their lower ends. The upper ends of the parts 37, 39 merge into each other. The upper ends of the parts 38, 40 merge into each other. The inclination of the parts 29, 30 of element 25 is less than the inclination of the parts 33, 34 of the element 26. The inclination of the parts of the element 26 is less than the inclination of the parts 37, 38 of the element 27. The inclination of the parts 31, 32 of element 25 is less than the inclination of the parts 35, 36 of the element 26. The inclination of the parts 35, 36 of the element 36 is less than the inclination of the parts 39, 40 of the element 27. The parts 29, 30, 33, 34 and 37, 38 of said elements are arranged at the portions 13, 14 and 15 of said member 12. The parts 31, 32, 35, 36, 39, 40 of said elements are arranged at the portions 14, 15, 16 of said member 12. The said parts 33, 34 are spaced a greater distance from the said parts 37, 38 than the said parts 33, 34 are spaced from the said parts 29, 30. The said parts 29 to 40, both inclusive, are disposed semi-diagonal with respect to the inner face of the said member 12. The points of emergence between the said parts 29, 31, said parts 33, 35 and said parts 37, 39 are disposed in alignment. The points of emergence between the said parts 30, 32, the said parts 34, 36 and the said parts 38, 40 are arranged in alignment, and the points of emergence between the said parts 31, 32, said parts 35, 36 and said parts 39, 40 are disposed in alignment. The element 24 is what may be termed straight and is not formed with inclined parts.

Secured to rear face of the elements 24, 25, 26, 27 and to the inner face of the member 12, as well as overlapping the points of emergence between the said parts 29, 31, said parts 33, 35 and said parts 37, 39 is an encased flexible stay member 41 which extends from the top to the bottom edges of body part 11 and it is also secured to binder 17. Secured to the rear faces of the elements 24, 25, 26, 27 and overlapping the points of emergence between the parts 30, 32, said parts 34, 36 and said parts 38, 40 is an encased flexible stay member 42, which extends from the top to the bottom edges of body part 11 and it is also secured to stay member 17. The stay members 41, 42 are secured in position by stitching.

Arranged in spaced relation with respect to opposite sides of the points of emergence between the said parts 31, 32, said parts 35, 36 and the said parts 39, 40 are encased flexible stay members 43, 44 which extend from the top to the bottom edges of body part 11. The stay members 43, 44 are secured to the resistance elements, the member 12 and the binder 17 by stitching. The stay members 43, 44 are of greater length than the stay members 41, 42.

There is disposed between and spaced equally from the stay members 41, 42, a pair of spaced parallel short encased flexible stay members 45, 46 arranged against the elements 24, 25 and 26. The lower end of members 45, 46 are positioned on the element 26. The upper end of the members 45, 46 is flush with the top edge of body part 11. The members 45, 46 are secured to ele-

ment 24, 25, 26 and to the member 11 by stitching.

There is correlated with the body part 11 a suspensory 47 including a pouch 48 and a pair of elastic coupling straps 49 secured at one end to the back wall 50 of the pouch 48. The front wall 51 of pouch 48 is slitted and the upper end of wall 51 is provided with a plurality of spaced female fastener sections 52. The binder 17 at its front has attached thereto a plurality of spaced male fastener sections 53 for correlation with the sections 52 for detachably connecting the pouch 48 in suspended relation with respect to the front of the body part 11. The other end of each of the straps 49 has attached thereto a female fastener section 54. The body part 11 at the lower portion of its rear is provided with a pair of spaced male fastener sections 55 for coaction with the male fastener sections 54 to detachably connect the straps 49 to the back of body part 11.

With respect to the modified forms of abdominal body braces, in accordance with this invention and as shown by Figures 8 to 15, they will have the stay elements 41, 42, 43, 44, 45 and 46 form parts thereof and which will be arranged relative to the body part of such modified forms in the manner as they are arranged with respect to the body part 11. The body part of each of the modified forms shown by Figures 8 to 15 will be of a contour corresponding to that of body part 11. The body part of each of the modified forms as shown by Figures 8 to 15 will have correlated therewith a suspensory corresponding in structure to the suspensory, which will be connected thereto and arranged relative therewith in the same manner as suspensory 57 is disposed relative to body part 11. Each of the modified forms, as shown by Figures 8 to 15, will include the same number of elongated elastic resistance elements disposed relative to its body part in the same manner as the elastic resistance elements 24, 25, 26, 27 are disposed relative to the body part 11. The elastic resistance elements employed in each of the modified forms as shown by Figures 8 to 15 will correspond in contour to that of the elastic resistance elements 24, 25, 26, 27.

With reference to Figures 8 and 9, the abdominal body brace is generally indicated at 64 and includes an elastic fabric body part 65 having arranged against its inner face a series of spaced superposed elastic resistance elements 66 (only two shown) each formed of an endless rubber strip having its lengthwise edges secured to body part 65 by zig-zag stitching 67.

With reference to Figure 10, the abdominal body brace is generally indicated at 69 and it includes an elastic endless body part 70 of sheet rubber having vulcanized to its inner face a series of superposed elastic resistance elements 71 (only two shown) each formed of an endless rubber strip.

The form of abdominal body brace shown by Figure 11 is generally indicated at 72, and it includes an elastic fabric body part 73 having vulcanized or cemented to the inner face a series of superposed elastic resistance elements 74 (only two shown) each formed of an endless rubber strip.

With reference to Figure 12, the abdominal body brace is generally indicated at 75, and it includes an elastic endless body part 76 of sheet rubber having vulcanized or cemented to its inner face a series of superposed endless resistance

elements 77 (only two shown) of elastic fabric.

The modified form shown by Figures 13 and 14 has the article generally indicated at 78 and it includes a body part 79 consisting of outer and inner like elastic endless sections 80, 81 respectively formed from sheet rubber. The said sections are suitably connected together and have interposed therebetween and connected to their inner faces a series of superposed endless resistance elements 82 (only two shown) of elastic fabric. The elements 82 may be vulcanized or cemented to the inner faces of sections 80, 81.

As to the form shown by Figure 15 and generally indicated at 83, it consists of a body part 84 formed of outer and inner endless elastic sections 85, 86 constructed from sheet rubber. Interposed between and vulcanized to the inner face of the section 86 is a series of superposed endless elastic resistance elements 87 formed from rubber. The sections 85, 86 are to be suitably secured together.

The elastic resistance elements shown by Figures 8 to 15 are of strap or tape-like form and function for the same purpose as the elastic resistance elements shown by Figures 1 to 7.

Otherwise than that as stated relative to the modified forms shown by Figures 8 to 15, such forms will be of the same construction as the form shown by Figure 1.

What I claim is:

1. A bracing belt for the purpose set forth comprising an elastic endless form fitting element for encompassing the body of the wearer and including a front, back and sides, superposed spaced endless elastic resistance elements of strap-like form disposed circumferentially of and secured to said form fitting element, each of the lower ones of the said resistance elements being formed with a front pair of oppositely extending downwardly inclined parts merging at their lower ends into each other at the vertical median of said front, and each of the said lower ones of the said resistance elements being formed with a rear pair of oppositely extending downwardly inclined parts merging at their lower ends into each other at the vertical median of the back.

2. A bracing belt for the purpose set forth comprising an elastic endless form fitting element for encompassing the body of the wearer, and superposed elastic endless resistance elements secured to one face of said form fitting element, the upper one of said resistance elements being arranged on the upper marginal portion of said face, the other ones of the said resistance elements having oppositely extending downwardly inclined parts disposed diagonally with respect to the front and back of said form fitting element.

3. A bracing belt for the purpose set forth including an endless elastic form fitting element for encompassing the body of the wearer having top and bottom edges, a front, a back and a pair of sides, an elastic endless binder overlapping said bottom edge and secured to said element, an upper elastic endless resistance member of band-like form secured to the inner face of and flush with the top edge of said element, a plurality of endless lower elastic superposed resistance members of band-like form secured to said face below the said upper member and disposed in spaced relation with respect to each other and to said upper member, the lower one of said lower members being positioned above said binder, spaced flexible upstanding stay means secured to said members binder and element, spaced flexible upstanding stay means spaced from said other

stay means and secured to said element and certain of said members, each of said lower members being formed with parts disposed in diagonal relation with respect to the front of said element and other parts disposed in diagonal relation with respect to said back.

4. A bracing belt for the purpose set forth including an endless elastic form fitting element for encompassing the body of the wearer having top and bottom edges, a front, a back and a pair of sides, an elastic endless binder overlapping said bottom edge and secured to said element, an upper elastic endless resistance member of band-like form secured to, flush with the top edge of and disposed circumferentially of said element, a plurality of endless lower elastic superposed resistance members of band-like form secured to said element circumferentially thereof below the said upper member and disposed in spaced relation with respect to each other and to said upper member, the lower one of said lower members being positioned above said binder,

spaced flexible upstanding stay means secured to said members and element, each of said lower members being formed with parts disposed in diagonal relation with respect to the front of said element and other parts disposed in diagonal relation with respect to said back, said front being of greater width than and having its lower portion disposed in depending relation with respect to said sides and back.

5. In an abdominal body brace, an endless elastic body part, superposed spaced elastic resistance elements connected to and providing said body part with circumferentially disposed spaced resistance zones, said elements being endless, spaced pairs of spaced aligned parallel vertically disposed stay means secured to said body part and to all of said elements, and a pair of spaced aligned parallel vertically disposed stay means arranged between and spaced from said pairs of stay means and secured to said body part and to certain of said elements.

PHILIP H. ROBBINS.
